UNITED STATES PATENT OFFICE.

GUSTAVE B. REISBACH, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRIC SWITCH.

1,071,087.

Specification of Letters Patent. Patented Aug. 26, 1913.

Application filed December 26, 1908, Serial No. 469,420. Renewed January 2, 1913. Serial No. 739,901.

To all whom it may concern:

Be it known that I, GUSTAVE B. REISBACH, a citizen of the United States, residing at Milwaukee, in the county of Milwaukee and State of Wisconsin, have invented new and useful Improvements in Electric Switches, of which the following is a full, clear, concise, and exact description, reference being had to the accompanying drawing, forming 10 a part of this specification.

My invention relates to improvements in electric switches, and more particularly to those adapted to be controlled from a distance.

15 The various objects and advantages of my invention will be hereinafter fully and clearly set forth.

According to the preferred form of my invention, I provide an automatically operated switch adapted to be controlled from a distance, with mechanical means for maintaining the same closed after being operated, and a tripping device adapted to be controlled from a distance for actuating said 25 means to open said switch. With such an arrangement, where the switch is operated by an electromagnet, it is only necessary to maintain the circuit of the operating magnet closed momentarily until the switch is closed, after which it may be opened. The 30 mechanical means will then hold the switch closed without any further expenditure of electrical energy until the tripping device is actuated.

35 For the purpose of more fully disclosing the characteristic features of my invention, I shall describe the device illustrated in the accompanying drawing, which embodies my invention in one form.

40 Of course, my invention is capable of various modifications.

The views in the accompanying drawings are as follows:

Figure 1 is a side elevation of the device, 45 parts thereof being shown in section; Fig. 2 is an enlarged view of part of Fig. 1, parts thereof being shown in section; Fig. 3 is an enlarged sectional view taken on line 3-3, Fig. 1; Fig. 4 is an enlarged sectional view 50 taken on line 4-4, Fig. 2; Fig. 5 is a sectional view taken on line 5-5, Fig. 2; Fig. 6 is a bottom plan view of the tripping magnet frame, and Fig. 7 is a perspective view 55 of part of the device.

The switch, or contactor, which I have

shown for the purpose of illustration, is of a conventional type. Briefly described, this contactor comprises a magnet frame 8 suitably secured to an insulating panel or base 9. Mounted in the frame is an electromagnet 10, having a movable plunger 11 connected by a pin 12 to a switch or contact arm 13 pivoted to the frame 8. The arm 13 carries a main contact 14 and an arcng contact 15, adapted to engage a laminated main 60 contact 16 and a pivoted arcng contact 17, respectively, said last mentioned contacts being supported by the magnet frame. A blow-out magnet 18 having pole pieces 19 is provided for disrupting the arcs formed between the arcng contacts. As before stated, this contactor is merely shown for the purpose of illustration, and it should be understood that the same may be of any 65 preferred type.

I shall now describe those parts which more particularly pertain to my invention. Secured to the insulating base 9, in any desirable manner, is frame 20. As shown, the frame 20 is provided with an upwardly 70 extending portion 21 secured to the insulating base between the same and the magnet frame 8 by a bolt 22. At its lower end the frame 20 is provided with a hollow rectangular portion adapted to receive an electromagnet 23, which will be hereinafter referred to as a tripping magnet. The magnet 23 is provided with a stationary core 26, and a movable plunger 27. The stationary core passes through a suitable aperture in 75 the bottom of the frame 20, and is provided at its end with an annular flange, which is secured by screws 28 to the frame 20. It will thus be seen that the core 26 serves to retain the magnet 23 in the frame. The 80 magnet 23 is additionally secured in the frame by means of set screws 24 provided with jam nuts 25. At its upper end the rectangular portion of the frame 20 is provided with an upwardly extending lug 29, 85 for the purpose hereinafter explained. Passing through suitable ears 30, provided at the upper end of the frame 20, is a pin 31, retained in place by cotter pins 32. Fulcrumed on the pin 31 is a bifurcated 90 weighted lever 33. The bifurcations of the lever 33 have upwardly extending projections 34 and 35, suitably spaced, and provided for the purpose hereinafter set forth. Fulcrumed on the pin 31, between the bi- 95

furcations of the weighted lever, is a substantially U-shaped member 36, having a downwardly extending lug 37 adapted to engage the lug 29 on the frame 20. The member 36 is best illustrated in Fig. 7. The upper ends of the legs of the member 36 are provided with lateral extensions 38, through which passes a pin 39. The pin 39 also passes through a pair of links 40, which are maintained thereon by cotter pins 41. The portions 38 of the member 36 are disposed between the projections 34 and 35 of the weighted lever, and are adapted to be engaged thereby and the member 36 moved 10 in one direction or the other as the weighted lever is moved. The upper ends of the links 40 are fulcrumed on the pin 12, which connects the switch arm 13 to the plunger of its operating solenoid. With this arrangement it will be seen that the links and the member 36 form a toggle connection between the switch arm 13 and the frame 20.

The function of the lug 37 will now be explained. The lug is so arranged to permit the member 36 to move outwardly until the pin connecting said member and the links 40 passes to one side of a straight line connecting the pivotal points of the links and the member 36. In such a position the toggle effectually locks the switch 13 in closed position, as illustrated in Fig. 1. Hence, as soon as the switch 13 is closed and locked, its operating winding may be deenergized. 35 To open the switch it is necessary to break the toggle.

The function of the weighted lever will now be explained.

Inasmuch as the weight is on the forward end of this lever, it is apparent that said weight normally tends to move said lever in a direction to cause the projections 34 thereon to engage the extensions 38 on the upper end of the member 36. Hence, when 45 the toggle is straightened upon the closure of switch 13, the weight tends to throw said toggle past the center to lock said switch in closed position. The rear end of the weighted lever is connected by a link 42 to the plunger 27 of the tripping magnet 23. Hence, when said magnet is energized, the weighted lever is rocked to cause the projections 35 thereon to engage the extensions on the member 36 and move said member to 55 break the toggle. This causes the switch 13 to open. Inasmuch as the projections on the weighted lever are a considerable distance apart, the projections 35 will not be brought into engagement with the toggle 60 until the weighted lever has been rocked some little distance by its operating magnet. Thus the weighted lever acquires considerable momentum before engaging the toggle, and consequently imparts a hammer blow thereto which quickly breaks said toggle.

gle. With this arrangement a comparatively small tripping magnet may be employed. As soon as the switch 13 is again closed, the weighted lever will cause the toggle to set to lock the switch closed.

It will thus be seen that by merely energizing the solenoid 10 for a short time the switch 13 will be closed and then the toggle will maintain it in closed position. The magnet 10 may then be deenergized. When 75 desired to open the switch, it is only necessary to energize the tripping magnet momentarily to operate the weighted lever to break the toggle.

Having thus described my invention, what 80 I claim as new and desire to secure by Letters Patent, is:

1. In combination, a pivoted switch, an operating solenoid therefor having a movable plunger connected to said switch, toggle links automatically set upon closure of said switch to mechanically lock the same in closed position, said toggle links when set being substantially in alignment with the plunger of said solenoid and a single device 90 tending to set said links and operable to impart a hammer-like blow thereto.

2. In combination, a pivoted switch, an operating solenoid therefor having a movable plunger connected to said switch, toggle links adapted when set to mechanically lock said switch in closed position and when set to be in substantial alignment with the plunger of said solenoid, and a member 95 tending to set said toggle links in locking 100 position and adapted to be actuated to break the same, said member having a predetermined degree of movement independent of said toggle links.

3. In combination, an automatically operated switch, a toggle connected with said switch, a weighted lever tending to move said toggle to lock said switch in closed position, and a solenoid for operating said weighted lever to break said toggle, thereby 110 releasing said switch.

4. In combination, an automatically operated switch, a toggle connected with said switch, a weighted lever tending to move said toggle to lock said switch in closed position, and a solenoid for operating said weighted lever to break said toggle, thereby 115 releasing said switch, said weighted lever having a limited movement independent of said toggle to cause the same to break said 120 toggle with a hammer blow when operated by said solenoid.

5. In combination, a switch, a solenoid having its plunger connected to said switch for operating the same, toggle links for 125 locking said switch in closed position, and a single pin connecting the plunger of said solenoid, said switch and said toggle links.

6. In combination, a pivoted switch, an operating solenoid therefor having a mov-

- able plunger, a pin connecting said switch to the plunger of said solenoid, toggle links connected to said pin and arranged to automatically lock said switch in closed position, 5 and electroresponsive means for operating said toggle links to release said switch.
7. In combination, a supporting base, a magnet frame mounted thereon, a solenoid mounted within said frame and having a 10 movable plunger, a switch pivoted to said magnet frame below said solenoid and connected to said solenoid plunger, a rigid member secured to said base below said switch, toggle links connecting said switch and said 15 member, and a movable device mounted on said member tending to automatically set said toggle links, to lock said switch in closed position and to be actuated to break said toggle links.
- 20 8. In combination, a switch, an operating solenoid therefor, a magnet frame arranged below said switch, toggle links connecting said magnet frame and said switch for locking said switch in closed position, a weighted 25 lever pivotally mounted on said frame, said weighted lever tending to set said toggle links and having a limited movement independent thereof, and a solenoid mounted in said magnet frame and having a plunger 30 connected to said weighted lever for actuating the same to impart a hammer blow to said toggle links to release said switch.
9. In combination, a pivoted switch, a solenoid for actuating the same, a stationary member arranged beneath said switch, 35
- links connecting said switch to said member, said links forming a toggle, one of said links having a projection thereon adapted to engage said stationary member when said links have been moved in one direction and 40 out of alignment to cause said links to lock said switch in closed position, a weighted lever tending to automatically set said links to lock said switch, and an electromagnet adapted to actuate said lever to cause said 45 links to release said switch.
10. In combination, a pivoted switch, a solenoid for actuating the same, a stationary member arranged below said switch, a 50 U-shaped member fulcrumed to said stationary members, links connecting said U-shaped member to said switch and forming a toggle for holding said switch closed, a weighted lever having bifurcated portions, said U-shaped member having portions disposed between the bifurcations of said weighted lever and arranged to be engaged thereby, said weighted lever being adapted to move automatically to set the toggle to lock said switch closed, and an electromagnet for actuating 55 said lever to impart a hammer blow to the toggle to break the same.

In witness whereof, I have hereunto subscribed my name in the presence of two witnesses.
